UNITED STATES PATENT OFFICE.

ELMER A. HENSAL, OF PANORA, IOWA.

TRUCK-SCOOP.

1,297,163.

Specification of Letters Patent. Patented Mar. 11, 1919.

Application filed August 8, 1917. Serial No. 185,178.

To all whom it may concern:

Be it known that I, ELMER A. HENSAL, a citizen of the United States, residing in Panora, county of Guthrie, and State of 5 Iowa, have invented a new and useful Improvement in Truck-Scoops, of which the following is a specification.

The object of this invention is to provide an improved construction for a multiple- 10 skid road grading and excavating machine.

A further object of this invention is to provide improved means for pivotally mounting skips on a grader frame, permitting vertical movement of said skips when 15 not under strain of taking on a load.

A further object of this invention is to provide improved means for raising the skips preliminary to the dumping operation.

A further object of this invention is to 20 provide improved means for adjusting the inclination of the skips and maintaining such adjustment irrespective of the vertical adjustment thereof.

A further object of this invention is to 25 provide independent means for dumping the skips.

My invention consists in the construction, arrangement and combination of elements hereinafter set forth, pointed out in my 30 claims and illustrated by the accompanying drawing, in which—

Figure 1 is a plan of my improved machine. Fig. 2 is a side elevation of the same. Fig. 3 is a front elevation of the truck and 35 frame, the latter being partly in section. Fig. 4 is a detail elevation, partly in section, showing means for elevating the skip and portions of the means for dumping the same. Fig. 5 is an elevation, on an enlarged 40 scale, of one of the crank shafts and its swivel members employed for adjusting the elevation of the skips. Figs. 6 and 7 are detail elevations, at right angles to one another, of the removable crank employed for 45 operating the dumping winches.

In the construction of the machine as shown the numeral 10 designates generally a main frame which is horizontally arranged and preferably is constructed of channel 50 beams suitably secured together. The frame 10 is supported at its rear end by relatively large ground wheels 11 and at its forward end by relatively small supporting and steering wheels 12 pivoted on a forward 55 axle 13 adapted for oscillation to steer the device in a common manner. A plurality of

skips of any common form, in this instance four in number and designated by the numerals 14, 15, 16, 17, are provided and are swung from the frame 10 and arranged one 60 ahead of the other thereon. Each skip preferably is provided with a removable cutting blade 18 at its forward margin, and with spaced handles 19, 20 projecting rearwardly from its rear side. For swinging 65

the skips 14, 15, 16, 17 from the frame 10 I prefer to employ brackets 21, 22, 23, 24 arranged in pairs transversely of and depending from the frame 10, each pair of brackets being adapted to support a skip between them. Intermediate of its ends each skip is provided with trunnions 25 engageable in curved slots 26 in the brackets, said slots being approximately vertical in their upper or forward ends and curving rearwardly at their lower ends as shown in Fig. 2. The trunnions 25 preferably comprise bolts extended through sleeves 27 70 slidable in the slots 26 and also adapted for rotary oscillation therein, said bolts being extended through the side of the skip and secured by nuts 28. Brackets 29, 30, 31, 32 are mounted on and rise from the frame 10, said brackets being arranged in pairs transversely of the frame and located substantially 75 above the brackets 21, 22, 23, 24 respectively. Winch shafts 33, 34, 35, 36 are arranged transversely of the frame and are journaled for rotation respectively in the pairs of brackets 29, 30, 31, 32. Each winch 80 shaft 33, 34, 35, 36 is provided, at either end or both, with crank handles 37 or other means for manually rotating the shafts. Each winch shaft 33, 34, 35, 36 is provided near its ends, and preferably inside the bearings, with drums or winches 38, 39. Chains 85 40, or cables, are fixed at their upper ends to and adapted to be wound on the respective drums 38 and 39, extend downwardly and have their lower ends secured to the 90 sleeves 27 of the trunnions, between the supporting brackets and sides of the skips. Thus means is provided for adjusting the vertical elevation of the skips independently, by rotating the shafts 33, 34, 35, 36 95 100 and winding or unwinding the chains 40 relative to the drums, the trunnions 25 traveling through the slots 26 in such operation.

Crank shafts 41, 42, 43, 44 are journaled 110 for rotary oscillation in the frame 10, one behind each of the skips. Each crank shaft

is provided at each end with a removable hand lever 45 for manually oscillating it. Swivel rings 46, 47 are pivoted to and depend from each of the crank shafts and are spaced apart and adapted to be engaged by the handles 19, 20 of the respective skips. The handles 19, 20 normally engage loosely in the swivel rings 46, 47, except during the operation of dumping the skips, and by such engagement determine the elevation of the rear end of the skips. When the crank shafts 41, 42, 43, 44 are oscillated, independently, the elevation of the swivel rings 46, 47, on the crank portions of said shafts, is altered, thus altering the elevation of the rear end of the skips and consequently adjusting the inclination of the skips relative to the horizontal. This adjustment may be made for each skip irrespective of the position of said skip in its supporting brackets, as determined by the winch mechanism above described, as the crank portions of the crank shafts have a range of movement of approximately one hundred eighty degrees in such operation, namely from a vertical depending to a vertical upstanding position through an arc described toward the skip which it controls, the rings 46, 47 swiveling on said shafts and always maintaining a substantially dependent position therefrom.

Winch shafts 48, 49, 50, 51 are arranged transversely and journaled for rotation in the frame 10, one forwardly of each of the skips 14, 15, 16, 17. As shown the winch shafts 48, 49, 50, 51 are journaled in bearings carried by the forward sides of the respective brackets 29, 30, 31, 32. A draft device 52 is fixed at one end to each of the winch shafts 48, 49, 50, 51 and is adapted to be wound thereon, and fixed at their opposite ends to rear portions of the respective skips 14, 15, 16, 17. The winch shafts 48, 49, 50, 51 are squared at one end, and a removable crank 53 is provided and adapted to engage such squared ends for manually rotating said shafts.

In practical use the skips 14, 15, 16, 17 are filled successively, the inclination being determined by manual adjustment of the crank shafts 41, 42, 43, 44 during such filling operation, as above set forth. After each skip is filled it may be elevated by operation of its winch shaft 33, 34, 35, 36, and held in such elevated position by any suitable means, such as ratchet and pawl devices 54 to prevent rotation of said shafts. In the filling operation the trunnions of the skips rest in the bottoms and at the rear ends of the curved slots 26, in positions of stable equilibrium not affected by the strain

of forcing the blades 18 through the earth. When all of the skips are filled and elevated the truck may be transported to any suitable place of deposit of the earth, the forward axle preferably having a tongue 55 or other suitable draft device through which tractive power may be applied from a tractor or the like for moving the truck both to fill the skips and to transport the load. When at the desired place of deposit the winch shafts 48, 49, 50, 51 are operated successively to wind the chains 52 thereon, thus elevating the rear ends of the skips and overturning said skips to the end of depositing their loads. In this operation the handles 19, 20 slip from the swivel rings 46, 47 and permit overturning of the skips, and are reengaged in said rings in any suitable manner when the skips are returned to normal positions.

This machine provides convenient means for moving large quantities of earth rapidly and with the assistance of a minimum number of laborers.

I do not desire to be understood as limiting myself to the precise construction and arrangement shown and described, as various modifications may be employed without departing from the spirit of my invention.

I claim as my invention—

1. In a machine of the class described, a truck frame, brackets arranged in transverse pairs spaced longitudinally of said frame, a skip mounted between each pair of brackets, said brackets being formed with vertical slots curved rearwardly at their lower ends, said skips being formed with trunnions pivoted in and also vertically adjustable of said slots, a crank shaft journaled in the frame behind each of said skips and formed with swivel rings, handles on and projecting rearwardly from said skips and adapted to engage loosely within said swivel rings, whereby the inclination of the skips may be separately adjusted, and means for adjusting said skips vertically by movement of said trunnions through said slots.

2. In a machine of the class described, a support, a skip mounted for oscillation and for vertical adjustment in said support, said skip being formed with rearwardly projecting handles, a crank shaft journaled in said support and provided with swiveled rings adapted to loosely receive said handles, and means for adjusting the elevation of said skip, said crank shaft being adapted for oscillation to adjust the inclination of the skip irrespective of its vertical elevation.

ELMER A. HENSAL.
